GASEOUS ELECTRIC DISCHARGE LAMP
DEVICE

Eduard G. Dorgelo, Eindhoven, Netherlands, assignor to General Electric Company, a corporation of New York

Application September 18, 1934, Serial No. 744,486
In Germany September 30, 1933

2 Claims. (Cl. 176—124)

The present invention relates to gaseous electric discharge lamp devices generally and more particularly the invention relates to illuminating systems incorporating such devices.

5 The starting potential of gaseous electric discharge lamps is appreciably higher than the operating voltage thereof and these lamps are operated in series with an impedance which absorbs the difference between the starting and 10 the operating voltage when said lamps are operating. When this external impedance consists of an ohmic resistance an appreciable amount of energy is wasted and when choke coils are used for this purpose the performance factor 15 is low.

20 The object of the present invention is to provide an illuminating system comprising a plurality of gaseous electric discharge lamp devices which is more efficient than prior systems incorporating such devices. Another object of the 25 invention is to provide an illuminating system the manufacturing cost of which is reduced to a minimum. Still further objects and advantages attaching to the device and to its use and operation will be apparent to those skilled in the art from the following particular description.

30 In accordance with these objects the illuminating system comprises a plurality of discharge lamps connected across the terminals of a current source the voltage of which is not capable 35 of starting the lamps. One of the current leads for the lamps is connected to one terminal of the current source through a resistance, or preferably through a choke coil, and a switch is provided by which this current lead is temporarily 40 connected with a point which, in regard to the other terminal of the current source, has a potential of sufficient magnitude to start the lamps. The system also comprises means for short-circuiting the above mentioned resistance or the choke coil.

45 When the system is started into operation the choke coil or the resistance is connected into the circuit and the switch connects the current lead with the point of higher potential. After the 50 discharge lamps have been started by this higher potential the connection between the lamps and the higher voltage point is broken. Potential is always impressed on the discharge lamps even 55 when this connection is broken since the current lead is connected to the terminal of the current source over the choke coil or the resistance. The discharge in the lamps is thus maintained in the lamps when the current lead is disconnected from the high potential and connected to the

terminal of the current source. After breaking the connection between the current lead and the point of higher potential, the choke coil or the resistance which has made the switching possible without danger of interrupting the discharge in the lamps is short circuited.

5 The potential supplied by the current supply source thus need be only sufficient to operate the lamps and need not be sufficient to start the lamps. The size of the external series impedances for the lamps thus can be considerably smaller than in the case where the voltage of the current source is sufficient to start the lamps for in the present case the impedances do not absorb the difference between the starting and the operating voltages of the lamps in the circuit during the operation of the lamps.

10 If the discharge lamps contain a metal difficult to vaporize, for instance, sodium, the vapor of which must have a certain pressure for participation in the light emission, then it is advisable 15 to maintain for some time the connection with the point of higher potential after the start of the discharge lamps. The lamps are then temporarily overloaded and rapidly heated to their 20 operating temperature.

25 When, during starting of the lamps, the current lead thereof is connected to the point of higher potential, then the above mentioned self-induction or the resistance is connected between 30 this point and the terminal of the current source with which this current lead is directly connected after the starting of the lamps. The choke coil or resistance prevents a short circuit between the higher potential point and the terminal. The 35 choke coil or the resistance is short circuited after the connection between this point of higher potential and the current lead has been broken. During the time between this interruption and the short circuit of the choke coil or of the resistance the latter are connected in series with the 40 discharge lamps. The self-inductance or the resistance must therefore be so dimensioned that the discharge in the lamps is not interrupted during this period. On the other hand they 45 must be so dimensioned that a short circuit or too great a current between the point of higher potential and the above mentioned terminal of the current source is avoided. In many cases a resistance does not meet both requirements and 50 therefore the use of a choke coil is preferred. The connection to the point of higher potential and the bridging of the choke coil or of the resistance are preferably made with the same 55 switch.

In the drawing accompanying and forming part of this specification three circuits embodying the invention are shown schematically.

Like numbers denote like parts in the figures.

- 5 Referring to Fig. 1 of the drawing the new and novel circuit comprises a number of gaseous electric discharge lamps 1 connected in parallel. Each of said lamps 1 is connected in series with a choke coil 2 between the current leads 3 and 4. Each of the discharge lamps 1 comprises thermionic electrodes and a gaseous atmosphere comprising a starting gas and the vapor of a difficultly vaporizable material, such as sodium. The current lead 3 is connected to the terminal 5 of the secondary transformer coil 6, while the lead 4 is connected to the terminal 9 of said secondary 6 through the choke coil 7 which is short-circuited, when desired, by the switch 8. Said lead 4 is connected by switch 10 to the end 11 of a special transformer coil 12 the other end of which is connected to the terminal 9.

When potential is applied to the above described circuit the switch 8 is open and the switch 10 is closed so that the potential between the point 11 and the terminal 5 of the transformer is conducted to the discharge lamps 1 which starts said lamps 1. Then the switch 10 is opened. After the opening of switch 10 the lamps 1 are connected across the terminals 9 and 5 of the transformer through the choke coil 7 so that the discharge in said lamps 1 is maintained. The choke coil 7, which is required in order to avoid a short circuit between the point 11 and the terminal 9 when switch 10 is in its closed position, is then short circuited by means of the switch 8 so that the current lead 4 is connected directly to the terminal 9.

The circuit shown in Fig. 2 comprises a three phase star connected transformer having terminals 13 and 17 and the mid-point 14. The current lead 3 of the discharge lamps 1 is connected to the terminal 13; the lead 4, through the choke coil 7, is connected to the zero point 14, while the latter lead 4 can also be connected by the switch 15 and the contact 16 to the terminal 17. The switch 15 can also be brought into contact with contact 18 which short circuits the choke coil 7.

50 The above described circuit is started into operation by moving the switch 15 into contact with contact 16 so that the voltage across the terminals 13 and 17 is applied to the lamps 1, which starts the lamps 1. After the lamps 1 have been started the switch 15 is moved from contact 16 to contact 18 whereby the connection between the current lead 4 and the terminal 17 is broken, the choke coil 7 is short circuited and the lead 4 is connected directly to the zero point 14 in sequence and the potential applied to the lamp circuit during operation of the lamps 1 is appreciably lower than that applied thereto during the starting of said lamps 1.

The circuit illustrated in Fig. 3 comprises a three phase transformer having the secondary coils 19 thereof connected in delta. The transformer also comprises two special coils 20 and 21 the points 22 and 23 of which supply a higher potential than the transformer coils 19. Between the points 24 and 25 a plurality of discharge lamps, indicated by crosses, are connected. The lamps 26 are connected in series

directly or, when desired, through small transformers, the primary circuits of which are connected in series.

The end 27 of the series circuit is connected to the terminal 25 through the choke coil 7 and is connected to the high potential point 22 by switch 15, when desired.

As shown in Fig. 3 a plurality of gaseous electric discharge lamps are connected in series across the terminals 24 and 28 and the terminals 25 and 28 as well as the terminals 24 and 25, when desired.

The lamps in each of these series circuits are started in the manner described in connection with Fig. 2.

Since the special transformer coils used to produce the higher potentials are in use but a short time they are wound of thin wires without danger, when disered, which reduces the manufacturing cost of the illuminating system.

While I have described my invention in connection with sodium vapor lamps it will be understood of course that I contemplate the use of lamps having the vapor of other metals as a light giving element, such as cadmium, magnesium, thallium, mercury, zinc or caesium, or amalgams or mixtures thereof, in my new and novel illuminating system.

What I claim as new and desire to secure by Letters Patent of the United States is:—

1. An illuminating system comprising in combination a plurality of gaseous electric discharge lamp devices, a transformer therefor, the starting voltage of said lamp devices being higher than the voltage across two terminals of said transformer and the operating voltage of said lamp devices being equal to the voltage across said transformer terminals, said transformer having a point thereon which supplies a higher voltage with respect to one of said terminals than that supplied by said terminals, said devices being connected through an impedance across two terminals of said transformer, means to connect said devices across said point and one of said terminals during the starting of said lamps and to connect said devices across the terminals of said transformer during the operation of said lamps and means to short circuit said impedance during the operation of said devices.

2. An illuminating system comprising in combination a plurality of gaseous electric discharge metal vapor lamp devices, a transformer therefor, the starting voltage of said lamp devices being higher than the voltage across two terminals of said transformer and the operating voltage of said lamp devices being equal to the voltage across said transformer terminals, said transformer having a point thereon which supplies a higher voltage with respect to one of said terminals than that supplied by said terminals, said devices being connected through an impedance across two terminals of said transformer, means to connect said devices across said point and one of said terminals during the starting of said lamps and to connect said devices across the terminals of said transformer during the operation of said lamps and means to short circuit said impedance during the operation of said devices.
